The ornamental design for a video game controller joystick cover, as shown and described.

DESCRIPTION

FIG. 1 is a front elevation view of a video game controller joystick cover showing our new design, the rear elevation view, the right elevation view, and the left elevation view being mirror images of the shown;

FIG. 2 is a cross-sectional view thereof taken along line 2-2 of FIG. 1;

FIG. 3 is a top plan view thereof;

FIG. 4 is a bottom plan view thereof;

FIG. 5 is an isometric view thereof; and,

FIG. 6 is an in-use isometric view thereof.

The broken lines in FIG. 6 of the drawings depict a video game controller with a joystick as environmental subject matter only and form no part of the claimed design.
